ABSTRACT

This relates to improved cathode retainer means for effecting positive positioning of a cathode within a companion electrode structure for use in a cathode ray tube electron gun. An end-emitting cathode is affixed within the aperture of a ceramic insulator disc and thence suitably positioned within a control grid electrode by an improved retainer means fabricated to exert sustained pressure against the supporting insulator. The improved retainer has a plurality of terminally oriented instanding projections of a bilaminate metallic material of predetermined flexure performance which are oriented to abut the insulator. Such bilaminate material comprises a first lamina of an active metallic alloy contiguously bonded along a common interface to a second lamina of a passive alloy material. The active alloy portion upon being subjected to a predetermined temperature during tube processing undergoes a metallurgic phase transformation effecting a volume change therein producing a definite modification of the shaping of the retainer projections thereby exerting positive and sustained pressure against the cathode positioning insulator.

CATHODE POSITIONING RETAINER

BACKGROUND OF THE INVENTION

This invention relates to means for positioning a cathode structure within an electron discharge device and more particularly to means for effecting positive positioning of a cathode within a companion electrode structure for use in a cathode ray tube.

In the manufacture of cathode ray tubes it has been conventional practice to employ cathodes utilizing heat responsive electron emissive materials as a source of electron beam energy. In devices of this nature, the cathode usually comprises a tubular metal sleeve capped on one end with a closure portion having electron emissive material adhered to the exterior surface thereof. A heater or resistive element is suitably disposed within the cathode tube to furnish the temperature level required to produce thermionic emission from the emissive material. A ceramic insulating disc having an axial opening therein to accommodate the cathode is utilized in a number of CRT electron guns to orient and support the cathode within a substantially cup-shaped control grid electrode having a defined aperture in the closed end thereof.

It is operationally essential to have the cathode positioned in a manner that the emissive material terminally disposed thereon is properly oriented and spaced relative to the associated control electrode aperture. It is also important that the cathode be securely disposed in its supporting wafer relative to the adjacent grid electrode to assure an adequate electrical insulative area or barrier therebetween. Furthermore, for proper operation of the tube, the cathode supporting insulator must be securely positioned within the associated encompassing electrode in a manner to prevent microphonics emanating from looseness of elements in the assembly.

The tubular cathode is disposed within the opening of the insulator disc and affixed therein by means of swages or ferrules which contact the supporting ceramic disc completely around the cathode member. An associated spacer means is positioned between the insulator disc and the electrode closure portion to effect predetermined spacing between the end-emitting surface of the cathode and the related aperture of the electrode. With the insulator disc being so positioned against the spacer means, a retainer for maintaining positioning of the disc within the grid electrode is inserted within the electrode in a manner to abut the under surface of the insulator and effect contiguous placement thereof against the spacer means. Being so positioned, the retainer is then bonded to the sidewall of the electrode thereby producing an integrated structure. In certain instances, it has been found that, due to operational thermal expansion and contraction, the components of the cathode electrode structure develop a degree of looseness which is a very undesirable condition. The factor of tightness assumes great importance in color cathode ray tube applications wherein it is imperative to have the cathode rigidly supported within the electrode structure. Any looseness of the cathode varies the critical operational cathode-to-grid spacing thereby generating spurious signals or microphonics which are visibly manifest during tube operation.

OBJECTS AND SUMMARY OF THE INVENTION

It is an object of the invention to reduce the aforementioned disadvantages and to provide an improved means for effecting positive positioning of a cathode within the associated electrode structure. Another object is to utilize tube processing temperature to effect positive tightness between the components of the integrated cathode electrode structure.

These and other objects and advantages are achieved in one aspect of the invention by providing an integrated cathode grid assembly wherein the ceramic spacer means supporting the cathode is positionally and rigidly held by an improved insulator retainer. This modified retainer is formed to have a plurality of terminally oriented instanding projections of a bilaminated metallic material of predetermined flexure performance which are oriented to abut the under surface of the cathode supporting insulator. The bilaminated material comprises a first lamina of active alloy material contiguously bonded along a common interface to a second lamina of a passive alloy material. The active lamina portion of the material undergoes a metallurgical phase transformation at a predetermined temperature during tube processing to effect a flexural stress in the projections contiguous to the cathode supporting insulator thereby modifying the bilaminated means to a substantially permanent secondary structural shape, the stress of which exerts positive and sustained pressure against the insulator.

BRIEF DESCRIPTION OF THE DRAWINGS

FIG. 1 is a sectional view illustrating a cathode-grid electrode assembly for use in a cathode ray tube electron gun. As shown, the cathode affixed within the supporting insulator is positioned within the control grid electrode and located therein by suitable spacer and retainer means; and

FIGS. 2a through 5b are respective plan and cross sectional views showing various embodiments of the cathode insulator retainer structure of the invention.

DESCRIPTION OF THE PREFERRED EMBODIMENTS

For a better understanding of the present invention, together with other and further objects, advantages and capabilities thereof, reference is made to the following specification and appended claims in connection with the aforescribed drawings.

With reference to FIG. 1, there is shown a representation of the cathode-control grid assembly portion 11 of a cathode ray tube electron gun. The control grid 13, for example, is a substantially cup-shaped electrode having an end closure 15 with a defined aperture 17 therethrough and an encompassing sidewall 19 therearound of a given internal dimensioning. Positioned within this control grid electrode is a cathode supporting insulator 21 having transverse dimensioning smaller than the internal dimensioning of the electrode member and formed to have an opening 23 therethrough wherein the tubular cathode 25 is affixed by ferrule-type modifications. A compatibly formed spacer means 27 is positioned between the cathode supporting insulator 21 and the grid electrode closure portion 15 to effect predetermined spacing between electron emitting surface 29 of the cathode and the aperture 17 in the grid electrode. An insulated thermionic heater means

31 is suitably disposed within the tubular cathode, being positioned through the open end thereof.

An insulator retainer 33 externally dimensioned to slide within the grid electrode, is abutted against the cathode supporting insulator 21 and affixed to the sidewall 19 of the control grid electrode 13 to effect contiguous placement of the insulator 21 against the spacer means 27. The retainer 33 has a plurality of terminally oriented instanding projections 35 of a bilaminated metallic material 37 of predetermined flexure performance. This material is comprised of a first lamina 39 of an active alloy material contiguously metallurgically bonded along a common interface 41 to a second lamina 43 of a passive alloy material. The active alloy material has the capability, on being subjected to a predetermined temperature, to undergo a metallurgical phase transformation effecting a shrinking volume change and resultant deformation thereof, while the passive alloy material has the capability of remaining in a substantially stable metallurgical phase throughout the temperature range wherein the predetermined temperature is included. This bilaminated material and the representative alloys comprising the same are the subject of a separate patent application, Ser. No. 206,124, now U.S. Pat. No. 3,743,485 filed Dec. 8, 1971, and a continuation-in-part patent application, Ser. No. 373,400, filed June 25, 1973, by Arnold J. Gottlieb and George A. Majesko and assigned to Wilbur B. Driver Company, Newark, N.J., which is a subsidiary of the assignee of the present invention. These patent applications disclose bilaminated materials for utilization in existing structures wherein the characteristics of the materials provide improved results thereof. In the present application, the generic bilaminated material of Ser. No. 206,124 is put to new usage in a newly designed retainer structure to provide results heretofore unattained.

FIGS. 2a and 2b delineate in greater detail the improved retainer means illustrated in FIG. 1. In this embodiment the whole of the retainer 33 is fabricated from the aforementioned bilaminated material. A plurality of spaced apart terminally oriented instanding projections 35 are integral extensions of material comprising the encompassing sidewall 36. The retainer structure is formed in a manner that the active material lamina 39 of the bilaminated material is oriented proximal to the cathode supporting insulator member 21. Prior to being incorporated into the cathode-control grid assembly, the improved retainer structure is formed to have a primary shape wherein the tab like radially instanding projections 35 are oriented substantially normal to the sidewall portion 36. During electron gun assembly, these tab like projections are placed contiguous to the cathode supporting insulator, and upon reaching a predetermined transformation temperature during tube processing a metallurgical phase change takes place in the active lamina of the structure thereby modifying the bilaminated means to a secondary structural shape which tends to exert positive and sustained pressure against the under surface of the insulator 21.

The predetermined temperature at which the active alloy lamina of the bilaminated material undergoes the desired metallurgical phase transformation is above the temperature level encountered in toto by the bilaminated material during retainer fabrication and subsequent tube assembly. The active alloy portion of the

bilaminated material is one that has a phase transformation temperature that is within the thermal range encountered during subsequent tube processing.

In an operating CRT electron gun, the insulator retainer component reaches a maximum temperature in the neighborhood of 340° C, but during processing of the tube the retainer is subjected to a varied range of temperatures. For example, during sealing of the electron gun mount into the envelope, a temperature of about 300° C is reached; during exhaust breakdown a thermal level in the vicinity of 650° C is encountered, and when associated heater conditioning is accomplished, the temperature is elevated to around 720° C. During subsequent cathode aging the retainer reaches a temperature of approximately 580° C. In considering the foregoing range of thermal levels, it is preferred that the metallurgical phase transformation of the active lamina material 39 takes place at a temperature level encountered early in the tube processing procedure so that the advantageous effects of the transformation can be beneficially utilized in a rigidly tightened cathode-electrode assembly during the remaining stages of processing.

An alloy suited for the active lamina portion of the bilaminated material is an iron-nickel alloy consisting essentially of 32 to 33 percent by weight of nickel with the balance of iron. The phase change transformation temperature of this alloy is about 300° C. One passive material for use with the above-noted active lamina is another iron-nickel alloy consisting essentially of about 36 percent by weight of nickel, and the balance of iron. Another suitable passive material for use in this combination is 1010 steel.

At the phase transformation temperature, the active material lamina of the projections 35 undergoes a crystal structure transformation from the martensitic phase to the austenitic phase whereat the active material shrinks in volume thereby deforming and inducing flexural stress in the bilaminated projections causing them to bend arcuately upward, as phantomed at 45, to exert increased pressure against the insulator disc 21. As previously mentioned, the active and passive alloy materials of the bilaminated structure are selected to have the phase transformation temperature of the active material within the tube processing temperature range, that is above about 300° C and below about 700° C. In other words, the passive material should remain in a stable metallurgical phase throughout the temperature range encountered by the material which should be up to substantially 800° C. When the critical temperature of phase transformation is reached, a modification of the shape of the structure is triggered by the active material and such change of shape is substantially permanently retained by the structure, the coefficients of thermal expansion of the active and passive laminae being substantially equal. Thus, the added flexural stress of the transformed material of the retainer will be sustained against the cathode supporting insulator regardless of the temperatures normally encountered thereafter in further tube processing and subsequent operation.

Another or second embodiment 47 of the improved cathode supporting retainer is shown in FIGS. 3a and 3b. In this embodiment the body portion 49 of the retainer member is made of a material such as stainless steel having a slightly inturned terminal edge 51 whereupon a plurality of separate spaced apart strips 53 of bilaminated material are suitably bonded as, for exam-

ple, by small area spot welds 55. The heat associated with the spot welding effects only minute and inconsequential areas of transformation. These radially oriented bilaminar strips 53 have the active alloy portion 39 facing outward in a manner to make contact with the under surface of the insulator 21. Upon the temperature consummated phase transformation, these strips each deform in an arcuate manner, as phantomed at 57, to exert increased pressure against the insulator disc.

Still another or third embodiment 59 of the invention is shown in FIGS. 4a and 4b wherein the retainer body 61 is fabricated of a material such as stainless steel. Attached to the terminal end 63 thereof are a plurality of substantially L-shaped bilaminar members 65 spaced apart and affixed to the internal surface of the retainer member 61 by small area spot welds 67. These L-shaped configurated members, having the active lamina 39 on the outer side of the "L," are located in a manner to extend beyond the terminal edge 63 of the retainer member. Such orientation allows for flexural stress or induced movement in two directions, substantially upward and outward as indicated by arrows 69 and 71 respectively.

An additional or fourth embodiment 73 of the invention is illustrated in FIGS. 5a and 5b, wherein the retainer member 75 is formed of bilaminar material having a plurality of separate arcuate ledges 77 oriented in substantially common plane, with the active lamina 39 being upwardly oriented. Each of these ledges is integral with the terminal periphery 79 of the retainer and extend in an inward manner therefrom. Each of the arcuate ledges has a pair of terminal apices 81 and 81'. When this embodiment of the retainer is subjected to the phase transformation temperature during tube processing, the inward portion of each arcuate ledge, in the vicinity of the apices, is subjected to greater deformation whereby the apices make substantially pressured two-point contact with the insulator disc 21.

Thus, several embodiments of an improved cathode positioning retaining structure has been described whereby a cathode retainer provides positive and sustained pressure to the cathode supporting insulator in a manner to permanently tighten the cathode-grid assembly. Such sustained pressure is expeditiously achieved by phase structure transformation of a portion of the bilaminar material of the retainer.

While there has been shown and described what are at present considered the preferred embodiments of the invention, it will be obvious to those skilled in the art that various changes and modifications may be made therein without departing from the invention as defined by the appended claims.

What is claimed is:

1. In a cathode ray tube electron gun structure, improved means for effecting positive positioning of a cathode within a substantially cup-shaped associated electrode having an end closure with an aperture therethrough and an encompassing sidewall therearound of given internal dimensioning, said improved positioning means comprising:

a supporting insulator disc having transverse dimensioning smaller than the internal dimensioning of said electrode and formed to have an aperture therethrough, said cathode being oriented within the aperture of said supporting insulator;

spacer means positioned between said insulator and said electrode closure portion to effect predetermined spacing between the emitting surface of said cathode and the aperture of said electrode; and an insulator retainer externally dimensioned to slide within said electrode and be affixed to the sidewall thereof in a manner to abut said insulator and effect contiguous placement thereof against said spacer means, said retainer having a plurality of terminally oriented instanding projections of a bilaminar metallic material of predetermined flexure performance, said material being formed of a first lamina of active alloy material contiguously metallurgically bonded along a common interface to a second lamina of a passive alloy material, said active alloy material upon being subjected to a predetermined temperature undergoes a metallurgical phase transformation effecting a volume change thereof, said passive material remaining in a substantially stable single metallurgical phase state throughout a temperature range wherein said predetermined temperature is included, said predetermined temperature being above the temperature encountered in toto by said bilaminar means during retainer fabrication and subsequent tube assembly, said predetermined temperature being a thermal level encountered during subsequent tube processing, said bilaminar means having a formed primary shape prior to being incorporated into said electrode, the active lamina portion of said primary shaped means of said retainer upon reaching said predetermined temperature during tube processing transforms to said metallurgical phase thereby modifying said bilaminar means to a secondary structural shape to exert positive and sustained pressure against said insulator.

2. The improved cathode positioning means according to claim 1 wherein said insulator retainer is comprised of said bilaminar material and wherein said terminally oriented instanding projections are integral extensions of said material.

3. The improved cathode positioning means according to claim 1 wherein the terminally oriented instanding bilaminar projections of said insulator retainer are separate spaced apart strips bonded to the terminal portion of said retainer and extended radially inward therefrom.

4. The improved cathode positioning means according to claim 1 wherein said instanding projections associated with said retainer means are in the form of a plurality of separate arcuate ledges oriented in a substantially common plane, each of said ledges being integral with the terminal periphery of said retainer.

5. The improved cathode positioning means according to claim 1 wherein the active material laminate portion of said bilaminar material is oriented proximal to the insulator member.

6. The improved cathode positioning means according to claim 1 wherein the predetermined phase transformation temperature of said active material lamina portion of said projections is above about 250°C and below about 700°C.

7. The improved cathode positioning means according to claim 1 wherein the active material lamina of said bilaminar means undergoes a crystal structure transformation from the martensitic phase to the austenitic phase at said predetermined temperature and

wherein the coefficients of thermal expansion of said active and passive laminae are substantially equal.

8. The improved cathode positioning means according to claim 1 wherein the active material lamina portion of said bilaminate materials shrinks in volume

5

when transforming from a martensitic to the austenitic phases thereby inducing flexural stress in said projections to exert positive and sustained pressure against said insulator.
